DESIGN FOR AN ESCUTCHEON

William E. Salyards, Jr., Highland Park, Ill., assignor to Crowe Name Plate & Manufacturing Co., Chicago, Ill., a corporation of Illinois

Application May 3, 1935, Serial No. 56,676

Term of patent 3½ years

To all whom it may concern:

Be it known that I, William E. Salyards, Jr., a citizen of the United States, residing at Highland Park, county of Lake, and State of Illinois, have invented a new, original, and ornamental Design for an Escutcheon, of which the following is a specification, reference being had to the accompanying drawing, forming a part thereof.

Figure 1 is a view in front elevation of an escutcheon showing my new design; and Figure 2, a section taken at the line 2 on Fig. 1 and viewed in the direction of the arrow.

I claim:

The ornamental design for an escutcheon, as shown.
